THIS IS A STYLIZED DRAWING OF A FURNACE GRATE. IT SHOWS A BASE FRAME 10 WITH SIDE RAILS 11 AND 12, AND CROSS FRAME MEMBERS 13 AND 14. A GRATE SURFACE 16 IS SHOWN AS A PLATE WITH AIR SLOTS 15. A REAR CROSS FRAME MEMBER 19 IS SHOWN AS A PLATE. A CENTER RAIL 17 IS SHOWN AS A PLATE. A CARRIER BAR 28 IS SHOWN AS A LONG BAR SUPPORTED BY STUB SHAFTS 25 AND 26. A LEVER 42 IS SHOWN AS A VERTICAL BAR.

SHAKER GRATE CONSTRUCTION

Charles V. Carroll, Minneapolis, Minn., assignor to Wm. Bros Boiler & Manufacturing Co., Minneapolis, Minn., a corporation of Minnesota

Application August 7, 1944, Serial No. 548,399

6 Claims.

(Cl. 110—39)

This invention relates to furnace grates and particularly to shaker grates for small, medium and large size boilers and furnaces wherein solid fuel is supported upon grate surfaces that are movable for shaking down or dumping the ash accumulation thereon. The invention relates in particular to grate surfaces composed of a plurality of grate bars or sections supported upon a transverse support or carrier bar.

It is an object of the invention to provide an improved grate design of rugged construction capable of withstanding heavy service over long periods and capable of being easily serviced. It is also an object of the invention to provide an improved carrier bar and grate bar construction capable of a maximum stability, and capable of providing a relative motion between grate bar and carrier bar so as to facilitate clearance of clinkers and hard ash accumulations without dislodgement of the grate bar from the carrier bar on which it is supported. It is a further object of the invention to provide improved simple, symmetrical, yet rugged, carrier bar and associate grate bar designs capable of either right-hand or left-hand mounting of the carrier bar, that may be manufactured easily without the necessity of complicated moldings.

Other objects of the invention are those inherent in the apparatus herein illustrated, described and claimed.

The invention is illustrated with reference to the drawings in which

Figure 1 is a fragmentary side elevational view, partly in section, illustrating the invention and showing, in full lines, the grates in normal operating position and showing, in dotted lines, the grates in elevated ash shaking or dumping position;

Figure 2 is a fragmentary view corresponding to that shown in Figure 1 except that a grate bar is shown in a moved position such as it assumes under certain conditions of operation;

Figure 3 is an enlarged fragmentary cross sectional view taken along the line 3—3 of Figure 1.

Throughout the drawings corresponding numerals refer to corresponding parts.

The furnace includes a base frame generally designated 10 composed of side and/or center rails 11 and 12 and cross frame members 13 and 14. The front cross frame member 13 is provided with air slots 15 and an upper grate surface 16 of any suitable design, and is fitted into the furnace frame construction as illustrated at 18 and may be cemented in place by suitable refractory 19. The rear cross frame member is likewise

solidly positioned on the furnace foundation and is seated in refractory as illustrated at 21. Upon the rear cross frame member there is positioned a grate cap member 22 having air slots 22a therein for feeding combustion air into the rear edge of the fuel bed. Referring to Figure 3 it will be observed that the side rails 11 and 12 of the frame are provided with suitable caps 11' and 12' having air slots 23 and 24 therein for feeding air into the marginal edges of the solid fuel bed supported upon the grate.

The rails 11 and 12 are provided with bearing notches 25 and 26 at evenly spaced intervals along the side rails. The bearing notches have a slightly conical bottom surface 25a and 26a and straight side walls 25b and 26b for convenience in manufacture and in order to centralize the carrier bar 28 and reduce friction of the carrier bar stub shafts 25' and 26' in the notches.

20 Into the oppositely spaced notches 25 and 26 on the two rails there are fitted the stub end shafts 25' and 26' of a carrier bar generally designated 28. The carrier bar has an intermediate grate bar supporting surface of the cross section shown at 30 in Figures 1 and 2. The carrier bar 28 is provided with cylindrical stub shafts 25' and 26' which fit into the bearing notches 25 and 26, respectively, the stub shafts being located at the level shown in Figure 3 so that the center of the stub shaft is at a level 32, as illustrated in Figures 1 and 2. The stub shafts are flattened off at the top if desired. The intermediate portion of the carrier bar has a cross section similar to the cross section of a railroad rail except that the base flange and vertical web are somewhat thicker than in a railroad rail. The head portion 33 is generally rectangular having a flat upper surface 34 and vertical side walls 35.

At the lower edge of the side walls 35 the walls blend through the curved surfaces 36 into the thickened web 37 which in turn is curved into the base section 38. It will be noted that the sidewalls of the base portion, indicated at 39, are slanted outwardly from top to bottom. The web 37 may be extended somewhat below the bottom flange 38, as indicated at 40, and at one point along the length of the carrier bar there is provided an integral downwardly extending carrier bar lever 42 which is cast integral with the carrier bar and is provided with integral stiffening gussets 43—43.

45 The levers 42 are vertical when the grate surface is in normal (here illustrated as level) position, and the levers are toward one end of the carrier bars. Furthermore the carrier bars are

50

of symmetrical cross-section about their vertical axis and lengthwise. Hence, the carrier bars may be turned around, end-for-end so as to bring all of the levers 42 at either side of the furnace for either right or left hand mounting of the shaker lever 47. This makes for simplicity of manufacture for a single style of carrier bar serves for either the right or left hand shaker installations. Also, for some furnaces having a large grate area the front and the back halves of the grate may be made so as to dump either toward the front or towards the back of the furnace or one in one direction and the other in the other direction and the shaker levers brought out one on the left side and one on the right side of the furnace. Thus a wide variety of grate and shaker arrangements are possible by using the symmetrical carrier bar construction here shown having the vertical shaker lever 42. The lower ends of the carrier bar levers 42 are finished in a curve, as shown at 44, and is apertured at 45, and the lower ends of all of the carrier bar levers 42 are tied together by pairs of spaced tie bars 47 having downwardly protruding portion 48 to which the shaker link 49 is attached, located one on each side of the levers 42.

Upon the rail shaped intermediate section of the carrier bar 28 there is positioned a grate, which may be a single large grate casting reaching across from one rail to the other, or a plurality of grate bars such as those here illustrated and generally designated 50. The grate bars 50 which are merely illustrative are here shown as identical construction and hence only one need be described. Each grate bar has a thickened head portion 51 of generally rectangular cross section and having a length and side elevational shape as illustrated in Figures 1 and 2. The fuel bed supporting surface of the grate bar head 51 and the sides thereof are provided with a plurality of notches for suitably supporting the solid fuel bed and for supplying combustion air thereto. Any suitable design may be used for the grate bar head, though I prefer the design herein illustrated and more fully described in my co-pending application Ser. No. 548,398, entitled "Grate," filed concurrently herewith. The grate bar head is undercut as illustrated at 52 and is chamfered as illustrated at 53 so that there is a slight overlapping of the grate bars positioned on adjacent carrier bars when the normal grate lever is positioned as illustrated under the bracket 55 in Figure 1. The undercut portion 52 of the rearmost tier of grate bars overlaps the cap plate 22, as illustrated in Figures 1 and 2, of the chamfered edges 53 of the frontmost tier of grate bars are overlapped by the tip portion 17 of the end cross frame and grate member 13, as likewise illustrated in Figures 1 and 2. Thus when the grate is in level position there is an unbroken fuel bed supporting surface, as shown in Figure 1.

Each of the grate bars is provided with a downwardly depending central web 57 of suitable thickness adequately to support and stiffen the head portion 51 of the grate bar. At one place along the grate bar the web 57 is notched from the bottom so as to fit the general contours of the rail shaped intermediate portion of the carrier bar. Thus, as will be observed in Figures 1 and 2, the notch generally designated 58 has a contour such that it fits in abutment with the side wall 39 of the base flange and extends along the line defined by side wall 39 to the point 59 and thence vertically in contact with the side wall 35 of the head portion of the carrier bar. The

notch is shaped so as then to follow the upper flat surface 34 of the carrier bar and thence extends downwardly along the somewhat slanting line 33' which has a slight clearance and forms a very slight angle with the vertical side wall 33 of the head portion. The notch thence continues along the line 61 to the angle 62 and thence extends toward the opposite wall of the notch so as to form the lug 63. It will be noted that clearance is provided at 64.

The clearance at 64 and the very slight clearance between the side wall 33 of the carrier bar and the corresponding surface 33' of the grate bar permits a slight relative motion of the grate bar with reference to the carrier bar, as illustrated for the grate bar 50A in Figure 2. When the carrier bars are oscillated by means of the links 49 and 47, ashes are shaken down into the ash pit below the grate surface and then when the link 49 is moved to a position such that the grate bar should be in the level position shown in Figure 1, it sometimes happens that ashes or clinkers will lodge between the undercut tip 52 of a grate bar such as that shown at 50A and beveled surface 53 of the grate bar 50, Figure 2, and the ash or clinkers 65 so lodged will not permit the grate bar 50A to resume its normal level position. When this happens the grate bar 50A so affected, rotates slightly with reference to its carrier bar 30A and shifts the clearance 64 to the opposite side as shown at 64', thus bringing the surface 61 and the surface 33' into engagement with the surfaces 39 and 33 of the carrier bar, respectively. Any dislodgement of the grate bar 50A under such conditions is prevented by the movement of the lug 63 under the bottom surface of the lower flange 30 of the grate bar. The degree of angularity between the vertical edge surface 33 of the grate bar head portion and the adjacent boundary 33' of the grate bar is determined by the desired and permissible degree of motion between the grate bar 50A and its carrier bar. The grate bar 50A thus out of level position does not prevent the remaining grate bars on the same or other carrier bars from resuming their normal level conditions.

Along the entire boundary of the notch 58 the flange 57 is thickened at each side so as to form a thickened border 66 running entirely around the notch. This serves adequately to stiffen the web 57 where it is cut away at the notch 58. It will be noticed that a greater portion of the grate bar overhangs the carrier bar at one side of the notch 58 than at the other side, as illustrated by the comparative sizes of the brackets 68 and 69, Figure 1. Accordingly there is a tendency for each grate bar to assume the position shown in Figure 1. The relatively close fit between the upper head portion 33-34-35 of the carrier bar and the corresponding portion of the notch and the dimension and position of the side wall of the notch 58 in contact with the surface 39, prevents the carrier from upsetting due to the overhanging weight on the end 68 or due to the fuel load on the grate bar. In addition the heavy overhanging end of each grate bar is supported due to the overlap with the short end of the grate bar on the next carrier bar as illustrated at 55 in Figure 1, and this also adds stability to the mechanism.

As many apparently widely different embodiments of this invention may be made without departing from the spirit and scope thereof, it is to be understood that I do not limit myself to the

specific embodiments herein except as defined by the appended claims.

What I claim is:

1. A furnace grate comprising spaced grate side frame members having spaced carrier bar journal recesses therealong, carrier bars extending from one side frame to the other side frame, each such carrier bar comprising an intermediate grate bar supporting portion that has an I-shaped cross-section substantially symmetrical about a vertical centerline and having a substantially flat upper flange and a bottom flange connected together by a central integral web and having trunnion ends fitted into said journal recesses, grate bars mounted side-by-side transversely on said grate bar supporting portion, each such grate bar being shaped to include a solid fuel supporting upper surface extending on one side of the carrier bar a greater distance than on the opposite side so as to be overweighted on said extending side of the carrier bar, said grate bars being provided with a downwardly extending supporting flange that has an upwardly extending notch along its lower edge so as to receive the carrier bar, said notch being slightly unsymmetrical about the vertical centerline of the carrier bar at the level of the upper flange thereof and having a dimensional width and shape so as to rest under normal conditions, against the upper substantially flat surface of the upper flange and embrace with slight clearance the edges of said upper flange, said notch also being unsymmetrical about the vertical centerline of the carrier bar at the level of the lower flange thereof, and shaped to rest against the edge of said lower flange corresponding to the overweighted side of the grate bar and

5 to rest in substantially spaced relationship to the opposite edge of said lower flange so as to provide a substantial clearance space and a lug on the wall of the notch extending toward and below said lower flange substantially across said clearance space.

2. The apparatus of claim 1 further characterized in that the depending stiffening and supporting flange of the grate bar is thickened around the margins of the notch.

10 3. The apparatus of claim 1 further characterized in that the end of that portion of each grate bar fuel supporting surface that extends the greater distance from the carrier bar on which it is supported, is undercut and the opposite end of the fuel supporting surface is chamfered to fit the undercut portion of the corresponding grate bar on the next carrier bar.

15 4. The apparatus of claim 1 further characterized in that means is provided for rotating the carrier bars a fraction of a revolution in a direction to elevate those end portions of the grate bars thereon that extend the greater distance from the carrier bars.

20 5. The apparatus of claim 1 further characterized in that the trunnion ends of the carrier bars protrude endwise from the I-shaped intermediate section at about the level of the upper flange of the I-shaped section.

25 6. The apparatus of claim 1 further characterized in that the I-shaped grate bar supporting portion of the carrier bar has a substantially wider lower flange than upper flange.

CHARLES V. CARROLL.
